UNITED STATES PATENT OFFICE.

WARDEN R. HUMPHREY, OF WILMINGTON, DELAWARE.

SHOWER OR NEEDLE BATH.

SPECIFICATION forming part of Letters Patent No. 552,839, dated January 7, 1896.

Application filed September 11, 1895. Serial No. 562,116. (No model.)

To all whom it may concern:

Be it known that I, WARDEN R. HUMPHREY, of Wilmington, in the county of New Castle and State of Delaware, have invented a new and Improved Shower or Needle Bath, of which the following is a full, clear, and exact description.

The object of the invention is to provide a new and improved shower or needle bath which is simple and durable in construction, very effective in operation, and arranged for convenient attachment to an ordinary bath-tub and adapted to be folded up for storage when not in use.

15 The invention consists principally of a casing open at the top and bottom and a perforated pipe fitting into the said casing along the sides thereof and adapted to be connected with the water-supply.

20 The invention also consists of certain parts and details and combinations of the same, as will be fully described hereinafter, and then pointed out in the claims.

Reference is to be had to the accompanying drawings, forming a part of this specification, in which similar characters of reference indicate corresponding parts in all the figures.

Figure 1 is a plan view of the improvement as applied. Fig. 2 is a perspective view of 30 the same, and Fig. 3 is a plan view of the casing as folded up.

The improved shower or needle bath is provided with a casing or box A, open at the top and bottom and connected at its sides A' and 35 A² with the ends A³ and A⁴ by hinges B, and the said ends A³ and A⁴ are made in two parts connected with each other by hinges B', so as to permit of folding the box or casing into the position shown in Fig. 3—that is, by folding 40 the ends A³ and A⁴ inward between the sides A' and A². The latter are provided near their upper ends and near the middle thereof with lugs C C', adapted to receive and support a perforated pipe D, made to conform to the 45 shape of the box and fitting on the sides and ends thereof with the perforations inside, so that water passing through the perforations issues in jets into the box.

The pipe D is provided at one end with an 50 inlet D', connected by a hose or other means E with one or both faucets F of the bath-tub

G, so that either hot or cold water may be sent into the pipe D and through the perforations thereof onto the object in the box. The bath-tub G is preferably provided on its 55 sides with suitable lugs H or other supports adapted to receive the lower edges of the sides A' and A² of the box to support the latter at the top, it being understood that the box is either made the width of the bath-tub 60 or narrower and the lugs H increased in size to support the box properly.

Now, when the several parts are in the position as shown in Fig. 1 then the person desiring to take a shower-bath enters the box 65 A, and the water issuing in jets through the perforations passes onto the whole or that part of the person's body extending into the box A, and the bather, by raising and lowering himself in the box, can readily expose 70 any part of his body to the jets of water.

It will be seen that by the arrangement described the jets of water surround the entire part of the body within the box or casing A, so that a complete washing of the body is as- 75 sured.

Having thus fully described my invention, I claim as new and desire to secure by Letters Patent—

1. A device of the class described, comprising a casing open at the top and bottom, and a perforated pipe fitting into the said casing along the sides thereof, and adapted to be connected with the water supply, substantially as shown and described. 80

2. A shower or needle bath, comprising a casing open at the top and bottom and having hinged sides and ends, and a perforated pipe adapted to fit into the said box along the sides and ends thereof, and adapted to be 85 connected with the water supply, substantially as shown and described.

3. A shower or needle bath, comprising a folding box or casing provided with lugs, and a perforated pipe adapted to fit into the said 90 casing when extended, and to be supported by the said lugs, substantially as shown and described. 95

WARDEN R. HUMPHREY.
